UNITED STATES PATENT OFFICE.

CHARLES B. DRAKE, OF NORFOLK, VIRGINIA.

VALVE.

Application filed January 28, 1926. Serial No. 84,517.

My invention relates to new and useful improvements in valves and more particularly to a thermostatically controlled valve adapted for regulating the fuel mixture to be admitted to an internal combustion engine or the like.

The principal object of the invention resides in the provision of a valve of the character described which is operated by heat conducted from the engine, the valve when the engine is cold allowing a relatively rich mixture to be admitted to the engine whereas when the engine is hot a relatively lean mixture will be admitted.

Another object of the invention resides in so forming the valve that a certain amount of the heat which is used for operating the same will pass through certain parts of the valve to heat the fuel mixture to effect a more efficient operation of the engine.

In the drawings I have illustrated the preferred embodiments of the invention as they now appear to me but it will be understood that such changes may be made as will fall within the scope of the appended claims.

In the drawings:

Fig. 1 is a side elevation with parts shown in vertical section.

Fig. 2 is a longitudinal vertical section through the valve with parts shown in elevation.

Fig. 3 is a horizontal section through the upper portion of the valve with parts shown in top plan, and

Fig. 4 is a transverse vertical section with parts shown in elevation.

In the drawings 1 indicates the fuel chamber of a carburetor and 2 a passage into which the fuel mixture is delivered through an opening 3 formed in the partition wall 4. The passage 2 communicates with the intake manifold, a portion of which is shown at 5 and from the intake manifold the fuel is delivered to the engine cylinders in the well-known manner. A portion of the exhaust manifold is shown at 6 and the clamping member 7 aids in securing both the intake manifold and the exhaust manifold to the engine.

My improved form of valve comprises an exteriorly threaded bushing 8 which is threaded into the upper wall of the passage 2. The bushing has the recess 9 extending from the bottom thereof and is provided at the top with the threaded opening adapted to receive the exteriorly threaded sleeve 10.

A lock nut 11 is provided for more securely holding the sleeve in engagement with the bushing. A plate 12 is threaded on the sleeve 10 or formed integral therewith and forms a support for the elongated plate 13 which has a central opening 14 of a diameter slightly larger than that of the sleeve 10 whereby it may be placed over the end of the sleeve and if desired rotated relative thereto. One end of the plate 13 is bent upwardly as shown at 15 and the opposite end is slotted to form the two extensions which are rolled to provide the eyes 16 and 17. An upwardly extending lug 18 is struck from the plate 13 and pivotally connected to this lug is a lever 19, said lever having the depending ears 20 which straddle the lug 18. A pin 21 passes through the ears 20 and lug 18 for pivotally connecting the lever to the lug. The outer end of the lever 19 is reduced as shown at 22, for a purpose to be later described, and the inner end of the lever is slotted as shown at 23.

A spring washer 24 extends around the upper end of the sleeve 10, as more particularly illustrated in Fig. 2 of the drawings, between the upper surface of the plate 13 and the under surface of an adjusting nut shown at 25, the adjusting nut being threaded upon the upper end of the sleeve 10. The spring washer 24 not only tends to hold the adjusting nut 25 in its adjusted position but acts to press the plate 13 into tight engagement with the plate 12.

A valve stem is shown at 26 and has its lower end pointed as shown at 27 to be received in the opening 3 in the partition 4. Adjacent the upper end of the stem is provided the groove 28 and intermediate the ends is a groove 29. A split ring 30 is received in the groove 29 and will engage the lower end of the sleeve 10 to limit the upward movement of the stem. As shown more particularly in Fig. 2 the split ring operates in the recess 9 of the bushing 8. The forked end of the lever 19 is adapted to engage in the groove 28.

A thermostatic member is shown at 31 and one end thereof is bent around and under one end of the plate 13 as shown at 32. The turned end 32 is secured to the plate 13 by means of the screw 33 or other suitable fastening. As shown more particularly in Fig. 2 the thermostatic member 31 is arcuate shaped and adjacent its free end is provided with the opening 34 through which extends

the reduced end 22 of the lever 19. In order to enclose the parts above the plate 13 I provide the cover cap 35. A flexible metal rod or wire is shown at 36 and is used not only for conducting heat from the exhaust manifold to the valve but for forming a pivot for connecting the cap 35 to the plate 13. The upper end of the conductor 36 is secured to the exhaust manifold 6 by the clamp 7 and the lower end is bent at right angles as shown at 37. This right angle extension 37 passes through the sides of the cap 35 and the eyes 16 and 17 thereby pivotally connecting the cap to the plate 13.

Having described the detail construction I will now endeavor to more clearly bring out the operation. It is a well known fact that when an engine is started and while still cold that it is desirable to admit a much richer mixture of fuel than is necessary when the engine is hot. With my improved form of valve the thermostatic member 31 operates directly upon the lever 19 to either raise or lower the valve stem 26. When the engine is cold the member 31 will be contracted and will press downwardly upon the outer end of the lever 19 thereby raising the inner end thereof and the stem 26. When in this position the pointed end 27 will be so positioned with relation to the opening 3 that a relatively rich mixture will be admitted to the intake manifold. When the engine becomes hot the heat is conducted from the exhaust manifold 6 by the conductor 36 to heat the thermostatic member 31 and thereby expand the same to raise the outer end of the lever 19. This movement will lower the valve stem 26 thereby admitting a much leaner mixture of fuel to the intake manifold. When the engine cools the thermostatic member will contract and act as a spring to raise the valve stem 26 through means of the lever 19 in the manner previously described. The downward movement of the inner end of the lever 19 may be regulated by the adjusting nut 25, it being understood that when the inner end of the lever is lowered it will engage the upper surface of the nut. The upward movement of the valve stem 26 is limited by the engagement of the split ring 30 with the lower end of the sleeve 10.

Having fully described my invention what I claim as new and desire to secure by Letters Patent is:

1. In combination with the intake manifold of an internal combustion engine, a valve for controlling the admission of the fuel mixture to the intake manifold, said valve including a body portion, a valve stem slidably mounted in the body portion, a lever pivotally connected to the body portion and engageable with the valve stem, a thermostatic member engageable directly with the lever, and means for conducting heat to the thermostatic member.

2. In combination with the intake manifold of an internal combustion engine, a valve for controlling the admission of the fuel mixture to the intake manifold, said valve including a body portion, a valve stem slidably mounted in the body portion, a lever pivotally mounted on the body portion and provided with a forked end engageable with the valve stem, a thermostatic member engaged with the opposite end of the lever, and means for conducting heat to the thermostatic member.

3. In combination with the intake manifold of an internal combustion engine, a valve for controlling the admission of the fuel mixture to the intake manifold, said valve including a body portion, a valve stem slidably mounted in the body portion, a lever pivotally connected to the body portion, said lever having one end reduced and the opposite end forked to engage the valve stem, a thermostatic member engaged with the reduced end of the lever, and means for conducting heat to the thermostatic member.

4. In combination with the intake manifold of an internal combustion engine, a valve for controlling the admission of the fuel mixture to the intake manifold, said valve including a body portion, a valve stem slidably mounted in the body portion, a lever pivotally connected to the body portion and engageable with the valve stem, a thermostatic member engageable with the lever, a cap pivotally connected to the body portion and adapted to enclose the lever and thermostatic member, and means for conducting heat to the thermostatic member.

5. In combination with the intake manifold of an internal combustion engine, a valve for controlling the admission of the fuel mixture to the intake manifold, said valve including a body portion, a valve stem slidably mounted in the body portion, a lever pivotally connected to the body portion and engageable with the valve stem, a thermostatic member engageable with the lever, a cap adapted to enclose the lever and thermostatic member, and common means for pivotally connecting the cap to the body portion and for conducting heat to the thermostatic member.

6. In combination with the intake manifold of an internal combustion engine, a valve for controlling the admission of the fuel mixture to the intake manifold, said valve including a body portion, a valve stem slidably mounted in the body portion, a lever pivotally connected to the body portion and adapted to operate the valve stem, adjustable means engageable with the lever for limiting the movement thereof, a thermostatic member engageable with the lever for operating the same, and means for conveying heat to the thermostatic member.

7. In combination with the intake mani-

fold of an internal combustion engine, a valve for controlling the admission of the fuel mixture to the intake manifold, said valve including a sleeve, a valve stem slidably mounted in the sleeve, a plate supported on the sleeve and rotatable relative thereto, said plate having an opening through which the sleeve loosely extends and means carried by the plate for operating the valve stem.

8. In combination with the intake manifold of an internal combustion engine, a valve for controlling the admission of the fuel mixture to the intake manifold, said valve including a sleeve, a valve stem slidably mounted in the sleeve, a plate supported by the sleeve and rotatable relative thereto, a lever pivotally connected to the plate and engageable with the valve stem, a thermostatic member engageable with the lever for operating the same, and means for conducting heat to the thermostatic member.

9. In combination with the intake manifold of an internal combustion engine, a valve for controlling the admission of the fuel mixture to the intake manifold, said valve including a sleeve, a valve stem slidably mounted in the sleeve, a plate supported on the sleeve and rotatable relative thereto, a lever pivotally connected to the plate and engageable with the valve stem, means carried by the sleeve for limiting the movement of the lever, a thermostatic member engageable with the lever for operating the same, and means for conducting heat to the thermostatic member.

10. In combination with the intake manifold of an internal combustion engine, a valve for controlling the admission of the fuel mixture to the intake manifold, said valve including a sleeve, a valve stem slidably mounted in the sleeve, a plate supported on the sleeve, a lever pivotally connected to the plate and engageable with the valve stem,

a nut adjustably mounted on the sleeve for limiting the movement of the lever, a spring member interposed between the plate and nut, a thermostatic member engageable with the lever for operating the same, and means for conducting heat to the thermostatic member.

11. In combination with the intake manifold of an internal combustion engine, a valve for controlling the admission of the fuel mixture to the intake manifold, said valve including a sleeve, a valve stem slidably mounted in the sleeve, a plate supported by the sleeve, a lever pivotally connected to the plate and engageable with the valve stem, a thermostatic member engageable with the lever for operating the same, and means for conducting heat to the thermostatic member.

12. In combination with the intake manifold of an internal combustion engine, a valve for controlling the admission of the fuel mixture to the intake manifold, said valve including a sleeve, a valve stem slidably mounted in the sleeve, a plate supported by the sleeve, a lever pivotally connected to the plate and engageable with the valve stem, a thermostatic member having one end connected to the plate and the opposite end engageable with the lever, and means for conducting heat to the thermostatic member.

13. A valve of the character described including a sleeve having an enlargement formed on the outer periphery thereof, a plate adapted to be received upon said enlargement and rotatable relative to the sleeve, means for holding the plate in engagement with the enlargement, a valve stem slideable relative to the sleeve, and a thermostatic member connected to the plate for operating the valve stem.

In testimony whereof I hereunto affix my signature.

CHARLES B. DRAKE.
